ELECTRIC SWITCH WITH QUENCHING LIQUID

Leonhard Haag, Frankfort-on-the-Main, Germany, assignor to Corporation of Voigt & Haeffner Aktiengesellschaft, Frankfort - on - the-Main, Germany

Application October 23, 1930, Serial No. 490,735
In Germany August 28, 1929

10 Claims. (Cl. 200—150)

This invention relates to a switch in which the contact takes place above the surface level of a quenching liquid and in which the arc produced when the circuit is broken is drawn into the liquid, so that the gases thereby produced can easily escape in an upward direction.

According to the invention a constriction or inwardly projecting flange is provided on the side of a hollow body in which the co-operating switch members are arranged. The constriction is provided beneath the stationary switch member, and therefore the gases and vapours arising from the breaking of the circuit within the quenching liquid cannot escape immediately through the hollow body, but are held back by the constriction therein, so that the pressure below the constriction rises. The compressed gases and vapours escaping through the constriction are blown into the arc, extinguishing the same immediately.

One constructional example of the invention consisting of two series-connected cut-out devices is illustrated in sectional elevation in the accompanying drawing.

Through a plate *a*, there project two hollow bodies or tubular vessels *b*¹ and *b*² containing a quenching liquid *r* e. g. water. Both the hollow bodies, which are provided with baffles *g*, have constrictions *s*¹ and *s*² formed by transverse partitions close above the surface of the liquid.

Through these hollow bodies *b*¹ and *b*² pass the leading in and leading out conductors *m*¹ and *m*² provided at their ends with stationary switch members or contact pieces *f*¹ and *f*², which are in the form of sleeves or sockets. A conducting switch cross bar *d* mounted on and actuated by an insulating rod *p* carries the movable switch members *e*, which are in the form of pins or plugs entering the sleeves *f*¹ and *f*².

The invention is distinguished by the fact that large powers can be switched off by it in an exceedingly short time and in a satisfactory manner. This may be explained in somewhat the following manner.

Owing to the fact that the switch members are so arranged that contact takes place above the liquid surface, and the arc that occurs upon switching off is drawn into the liquid, the removal of the vapours produced by and hindering the breaking of the circuit within the quenching liquid is facilitated, and yet a rapid quenching of the arc is at the same time obtained by the liquid cooling it. The vapours arising from the breaking of the circuit cannot however escape immediately through the constrictions *s*¹ and *s*² of the hollow bodies *b*¹ and *b*² serving as discharge pas-

sages, but are held back by the constrictions therein, so that the pressure below the constrictions or nozzles *s*¹ and *s*² rises. By this pressure there is produced a strong current of gases and vapours through the constrictions *s*¹ and *s*², which is blown into the arc and extinguishes the same immediately. The baffles *g* serve merely as a protection against liquid particles being thrown out, and for the cooling of the vapours that escape. The upper parts of the tubular members *b*¹ and *b*² form funnel- or chimney-like means of exit for the extraordinarily hot and rapidly streaming gases and vapours escaping through the constrictions of the said members. The upper parts of the members *b*¹ and *b*² prevent damage being caused by said gases and vapours and the flashing over of the arc to bodies which may be placed in the neighbourhood of the switch. The hollow bodies *b*¹ and *b*² should be filled preferably with a quenching liquid which develops a large quantity of gas and vapour when the arc is drawn into it. The switch according to this invention acts like a compressed-gas switch but produces the gas stream blowing out the arc by decomposition of the quenching liquid. The nozzles *s*¹ and *s*² closely surround the rods *e* so that the parts of the tubular members *b*¹ and *b*² below the nozzles being adapted to serve as pressure chambers are closed very tight as long as the rods *e* have not been withdrawn from said nozzles.

What I claim is:—

1. An electric switch comprising stationary and movable switch members, a hollow body closed at the bottom and containing a quenching liquid, the said hollow body surrounding and enveloping the stationary and movable switch members, a constriction in the hollow body, the stationary switch member being arranged above the liquid surface and above the constriction, and the movable switch member extending upwards through the constriction to make contact with the stationary switch member and being adapted to be withdrawn downwards through the constriction when the switch is opened, thereby drawing the arc through the constriction into the liquid.

2. An electric switch comprising tubular bodies closed at the bottom and containing a quenching liquid, stationary and movable switch members within the said bodies, the stationary switch members being arranged above the surface of the quenching liquid, the movable switch members being adapted to make contact with the stationary switch members and to be moved downwards to open the switch, each of the tubular bodies having an inwardly projecting flange ar-

- ranged beneath the stationary switch member and apertures in these flanges in line with the path of movement of the movable switch members, the distance between the stationary switch members and the apertures within the flanges being less than the length of the arc occurring as the switch opens. 6. An electric switch comprising a tubular member, a horizontal partition in the said member, an opening in the partition forming a nozzle, co-operating contact pieces mounted to make contact with one another above the partition, the point of contact of the contact pieces being surrounded by air, and the space below the partition being filled with a quenching liquid, one of the contact pieces being formed by a plug and being movable through the nozzle, and the distance between the nozzle and the point of contact of the contact pieces being less than the length of the arc occurring as the switch opens. 80
3. An electric switch comprising hollow bodies closed at the bottom and containing a quenching liquid, stationary switch members arranged within the hollow bodies above the surface of the quenching liquid, movable switch members extending upwards through the quenching liquid within the hollow bodies and adapted to make contact with the stationary switch members and to be moved downwards to open the switch, and a constriction in each of the hollow bodies arranged under the stationary switch member and closely surrounding the movable switch member, the distance between the stationary switch members and these constrictions being less than the length of the arc formed when the switch is switched off. 7. An electric switch comprising a chamber open at its top, a stationary contact arranged within said chamber, a movable contact rod co-operating with said stationary contact and adapted to be moved downwards to open the switch, the lateral walls of said chamber enveloping both said stationary contact and said contact rod, the point of contact being surrounded by air, a vessel containing a quenching liquid below said chamber, said chamber being separated from said vessel by a horizontal partition, an opening within said partition concentric with the path of movement of said rod, the lateral walls of said opening closely surrounding the said rod, and the distance between the said point of contact and said opening being less than the length of the arc occurring as the switch opens. 90

4. An electric switch comprising a tubular member containing a quenching liquid, a stationary switch member in the form of a socket, a movable switch member in the form of a plug adapted to engage therewith, the tubular member surrounding the socket and the plug, a constriction in the tubular member below the socket, the diameter of the constriction being substantially equal to the diameter of the plug, this plug extending upwards through the constriction to make contact with the socket above the liquid surface and being adapted to be withdrawn downwards out of the constriction when the switch is opened, and the distance between the socket and the constriction being less than the length of the arc formed when the switch opens. 8. An electric switch comprising a vessel closed at its top and containing a quenching liquid, a bore in the top of the said vessel, a contact plug adapted to be moved downwards extending through the said bore, the diameter of the said plug being substantially equal to the diameter of the said bore, a stationary contact arranged on the outside of the said vessel co-operating with the said contact plug, the said stationary contact being surrounded by air, the distance between the said stationary contact and the said bore being less than the length of the arc formed when the switch opens, and a tubular exhaust member above the said vessel surrounding said stationary contact. 110
5. An electric switch comprising co-operating contact pieces mounted to make contact with one another in air, one of the said contact pieces being formed by a plug a tubular exhaust member surrounding and enveloping both said contact pieces, a vessel filled with quenching liquid arranged below the point of contact of the contact pieces, the said vessel being joined to the said tubular exhaust member and being closed above the liquid surface with the exception of an opening concentric with the path of movement of the plug, the lateral walls of this opening closely surrounding the plug, and the distance between the said point of contact and the said opening being less than the length of the arc occurring as the switch opens. 9. An electric switch as claimed in claim 7, wherein the lateral walls of the chamber enveloping the contacts are integral with those of the vessel containing the quenching liquid. 115
10. An electric switch as claimed in claim 8, 125 wherein the vessel containing the quenching liquid is integral with the tubular member above the said vessel.
